CLAIM

The ornamental design for a sports net frame, as shown and described.

DESCRIPTION

FIG. 1 is a perspective view of a sports net frame showing our new claimed design with environmental structure; FIG. 2 is a perspective view of the sports net frame; FIG. 3 is a front elevational view thereof; FIG. 4 is a back elevational view thereof; FIG. 5 is a left-side elevational view thereof, the right-side elevational view being a mirror image thereof; FIG. 6 is a top plan view thereof; and, FIG. 7 is a bottom plan view thereof. The sports net frame is shown with a symbolic break in its width. The appearance of any portion of the article between the break lines forms no part of the claimed design. Broken lines in the figures illustrate environmental structure that forms no part of the claimed design.
